UNITED STATES PATENT OFFICE.

THOMAS OTTESEN, OF STAVANGER, NORWAY.

MEANS FOR OPENING TIN CANS.

1,201,339.

Specification of Letters Patent. Patented Oct. 17, 1916.

Application filed March 16, 1916. Serial No. 84,505.

To all whom it may concern:

Be it known that I, THOMAS OTTESEN, a subject of His Majesty the King of Norway, residing at Lervigsvei 11, Stavanger, Norway, a manufacturer, have invented a certain Improved Means for Opening Tin Cans; and I do hereby declare the following to be a full, clear, and exact description of the invention, such as will enable others skilled in the art to which it appertains to make and use the same.

This invention relates to means for opening tin cans, of the kind wherein an opening tongue is provided by weakening lines in the lid inclosing a tongue shaped area, which tongue after being partially broken away from the lid is adapted to be engaged by a key for the completion of the opening operation.

20 The invention differs from arrangements known before, in that a second weakening line, extending at right angles to the longitudinal center line of the tongue shaped area, has its ends turned laterally away from the tongue and extended to the seamed edge of the lid. A smaller area is thus inclosed, which when pressed downwardly by the opening key is torn away along the said second weakening line and bent inwardly into the can, thereby providing an aperture into which the opening key may be inserted so as to lever up the end of the tongue shaped area which may afterward be torn away in the usual manner by engaging said tongue end 35 with a slot formed in the key stem and rotating the latter about its axis.

In the annexed drawings which show a tin can in accordance with this invention:— Figure 1 is a plan view of the can, Fig. 2 40 is a longitudinal section thereof before opening, Fig. 3 shows a similar section after the opening has been commenced, and Fig. 4 shows a convenient construction of opening key.

45 The ends of the weakening line 1 are arranged in the lid as usual, and inclose a tongue shaped area, and terminate at a second weakening line 2 extending transversely of the longitudinal center line of the tongue.

The ends of this transverse weakening line 50 are turned laterally away from the tongue and extended to the seamed edge 8 of the lid, thereby inclosing a smaller area 3. When pressed downwardly by the opening key 4 (Fig. 2) this smaller area 3 will be torn away 55 from the lid along the weakening line 2 and bent inwardly into the can. The end of the opening key is then inserted through the aperture thus formed, and the end 5 of the tongue shaped part of the lid is levered up 60 by the key, as shown in Fig. 3, into position for engagement by the slot in the key stem, when the opening operation is completed in the usual way by rotating the key stem about its axis. The tongue shaped part is advantageously provided with a depression 6 which affords a good hold for the key during the completion of the opening operation.

While the weakening lines 1 in the lid are usually pressed into the under face of the lid, 70 the weakening line 2 is, as shown, pressed into the upper face. The area 3 is, therefore, when pressed downwardly, more easily torn loose along the weakening line 2 than were the latter pressed into the under face of 75 the lid.

An ordinary opening key may be used; it will, however, be preferable to use a key, as shown in Fig. 4, the end 7 of which is flattened and brought to a point. 80

What I claim and desire to secure by Letters Patent of the United States is:—

1. In a tin can, the combination of a can body, and a lid having a weakening line inclosing a tongue shaped area, another weakening line in the lid extending transversely of the tongue and inclosing a second area smaller than said tongue shaped area, the ends of said first mentioned weakening line extending to said second weakening line, and the ends of the said second weakening line being turned laterally away from the tongue and extended to the seamed edge of the lid. 85

2. In a tin can, a tongue shaped area inclosed by a weakening line in the lid, and a smaller area bounded by a weakening line in the lid and by the seamed edge of the latter. 90 95

3. In a tin can, a lid provided with an area inclosed by a weakening line, and with a second weakening line inclosing a smaller area which is pressed downwardly into the can when opening the latter, said second weakening line being pressed into the upper face of the lid.

In testimony whereof I have hereunto set my hand in the presence of two witnesses.

THOMAS OTTESEN.
